UNITED STATES PATENT OFFICE.

PERCY L. SIBOLE, OF NEWARK, NEW JERSEY, ASSIGNOR TO KLYMAX FEEDER COMPANY, A CORPORATION OF NEW JERSEY.

PRINTING PRESS.

Application filed December 18, 1923. Serial No. 631,315.

To all whom it may concern:

Be it known that I, PERCY L. SIBOLE, a citizen of the United States, and resident of Newark, in the county of Essex and State of New Jersey, have invented certain new and useful Improvements in Printing Presses, of which the following is a specification.

This invention relates to improvements in printing machines or presses and has particular reference to improvements relating to the automatic paper feeding attachment to job presses.

The object of the invention is to provide a novel, practical and simple mechanism for removing or detaching the paper feeding mechanism from the press in order to make ready or to provide for manual feeding or for other purposes.

The prior art contains automatic feeders for job presses adapted to be moved to one side of the press in order to accomplish any of the aforesaid purposes. Such constructions, however, necessarily require a good deal of space alongside the press, and this space serves no particular purpose when the press is automatically operated.

This invention provides a construction whereby the paper feeding mechanism is lifted off the press and elevated directly above the same, thus accomplishing the purpose of removability without requiring more space than is necessary for the operation of the press.

The invention is disclosed in connection with a Chandler & Price press equipped with an automatic feeder of the Morrison type shown in U. S. Patent Number 1,476,829 dated December 11th, 1923.

Referring to the accompanying drawings illustrating the preferred form of the invention

Figure 1 is a side view of a printing press with automatic feeder attachment embodying the invention, parts being omitted, and Figure 2 is a front view of the press looking from the left in Figure 1.

The printing press is identified by the frame 1, the platen 2 and the form member 3. On the latter is suitably pivoted an arm 4 carrying a suction paper separating device 5 of the kind disclosed in the U. S. Patent Number 1,394,181, for separating the topmost sheet of paper from the pile 6 resting on the paper support 7. The latter in turn is mounted on the feed table 8.

Reference is made to the patents aforesaid for a complete disclosure of the detailed construction and operation of the paper feed attachment. For the purposes of this invention, the paper feed table 8 and paper support 7 represent the paper feed mechanism, the element 5 being properly classified as a separating device.

Referring now more particularly to the subject matter of this invention, the paper feeding mechanism aforesaid is supported on a bracket 9 having shoulders 10 and 11 adapted to receive the feeding mechanism and whereby the same is properly registered or positioned on the press. The bracket 9 may be duplicated for the two sides of the press, but preferably a smaller similar bracket 12 is used on the one side, in this case the left side, as shown in Figure 2.

To the bracket 9 is secured a substantial foot piece 13 which supports an upwardly inclined guide member 14 of any suitable form. At each end of the said guide member is mounted a pulley or sprocket wheel 15 and 16 over which pass a cable or chain 17. On the outside of the guide member 14 a weight 18 is secured to the cable 17, while on the inside or the side facing the press, there is secured to the cable a bracket 19. The latter is adapted to grip in under the feed table 8 to lift the same, see Figure 2, the bracket 19 having a heavy lug 20 for this purpose. 21 is a handle for rotating the lower pulley 15.

During the normal operation of the press attachment, the feeding mechanism rests on the supporting brackets, as shown in full lines in the drawings and the weight 18 is at the top of the guide member. When it is desired to remove the feeding mechanism, the pulley 15 is rotated whereby the chain is caused to move over the two pulleys and the bracket 19 lifts the feeding mechanism away from the press. The weight of the feeding mechanism as it is lifted bodily above the press is counterbalanced by the weight 18. In this manner the feeding mechanism may be raised to any height within the limit of the device and will remain at such height until, by reverse rotation of the pulleys, the feeding mechanism is lowered into operative relationship with the press, when the feeding mechanism will automatically be properly positioned by the registering shoulders 10 and 11.

When the feeding mechanism is elevated, the separating device 5 is preferably first swung forward out of the way as indicated in Figure 1 in dotted lines of the arm 4.

6 It will be observed that the elevating device herein disclosed does not require any extra space alongside the press, and that when the feeding mechanism is elevated it is completely out of the way and permits 10 free access to the press.

The structural details may of course, be altered and changed without departing from the principle of the invention and the scope of the appended claims.

15 I claim:

1. The combination with a printing press, of a paper feeding device therefor, mechanism for moving said device into and out of operative relation with the press comprising

ing upwardly extending guiding means secured to the press, a conveyor mounted in said guiding means, means on said conveyor engaging said feeding device for the purpose aforesaid and a handle for operating the conveyor. 20

2. The combination with a printing press, of a paper feeding device therefor, mechanism for moving said device into and out of operative relation with the press comprising a guide member secured to the press and extending upwardly in an inclined position in over the press, a conveyor mounted on said guide member, a bracket on said conveyor adapted to engage said feeding device to raise and lower the same and a handle for operating the said conveyor. 25

30 P. L. SIBOLE.
